COLONEL COONEY, OF ADA, OHIO.

COMBINED WEATHER STRIP AND SASH FASTENER.

Application filed April 6, 1922. Serial No. 550,085.

To all whom it concern:

Be it known that I, COLONEL COONEY, a citizen of the United States, residing at Ada, in the county of Hardin and State of Ohio, have invented a new and useful Combined Weather Strip and Sash Fastener, of which the following is a specification.

This invention relates to combined sash fasteners and weather strips.

10 The object is to provide a simple, cheaply constructed device of this class, which may be easily applied in position on the upper faces of the meeting rails of window sashes for the purpose of locking the sashes together to prevent any vertical movement, and at the same time, when so locked, to cover the crack or space between said rails from end to end, to exclude cold air from entering, the said device occupying a minimum amount of space upon the rails and being readily accessible from within the room to unlock the sashes, when it is desired to open the same.

25 A full and complete understanding of the invention may be obtained from a consideration of the following detailed description taken in connection with the accompanying drawing forming a part of this specification; it being understood that while 30 the drawing shows a practical form of the invention, the latter is not to be confined to strict accordance therewith, but may be changed or modified, so long as such changes or modifications mark no material departure 35 from the salient features of the invention, as specifically pointed out in the appended claims.

40 In the drawing, in which similar reference characters designate corresponding parts throughout the several figures:—

45 Fig. 1 is a perspective view of the meeting rails of an upper and lower sash together with portions of a window frame and showing the improved device mounted on said rails.

50 Fig. 2 is a top plan view of one member of the device which is carried by the inner meeting rail of the lower sash and constitutes the combined locking member and weather strip.

55 Figs. 3 and 4 are enlarged detail, transverse sectional views through the rails and showing the device in and out of operation respectively.

55 The principal leakage of cold air into a room is generally through the crack or space

between the meeting rails of the upper and lower sashes of a window, and numerous sash fasteners have been devised for the purpose of preventing the unauthorized opening of the said sashes, and at the same time to draw the meeting rails together tightly enough to exclude the entrance of cold air, but this has been found unsatisfactory for the reason that considerable play must be provided in the sash channels and around the parting strips to permit said sashes to move laterally for the purpose of binding the sashes together by such locks, and this play or freedom offsets the advantage of the locking action by allowing the entrance of air entirely around the sashes.

60 In the use of the present fastener, a more tightly fitting sliding connection between the sashes and the channels and around the parting strips may be maintained, for the present lock does not contemplate the bringing together of the meeting rails thereof in order to exclude the air, but is designed to 65 cover the gap or space by a plate having a padding on its under side extending from end to end of the rails, said plate being adapted to be moved outwardly over the inner rail member across the gap and onto the adjacent outer rail, and to be wedged 70 tightly down upon the surfaces by means of keepers carried by the outer member.

75 The invention comprises an elongated plate 1 formed of some suitable metal, preferably steel, so as to permanently retain its 80 shape under continued operation, the said plate 1 being somewhat less in width than the width of the upper rail 2 of the lower sash, to which said plate is slidably secured. The ends of the plate 1 terminate short of 85 the opposite parting strips 3, which are present in substantially all sliding sash window frames for the purpose of dividing the inner faces of the said frame into the usual sash channels.

90 Suitably secured to the under face of the plate 1, as by cement, rivets or otherwise, is a layer of felt 4, which is coextensive with the plate and is adapted to rest directly upon the upper face of the meeting 95 rail 2 of the lower sash 5. The plate is provided, at points substantially midway between the center thereof and each end, with transversely disposed slots 6, terminating at each end adjacent to the longitudinal side edges of the plate, and these 100 slots also extend through the felt facing on

the under side thereof. Screws 7 are driven through the slots 6 and into the meeting rail 2, the said screws having their heads resting upon washers 8, the binding action of the screws being such as to prevent any up or down motion of the plate thereon, and at the same time readily permitting a sliding movement of the plate upon the upper face of the rail 2.

10 A plurality of locking bars 9, preferably three in number, are secured, as by rivets 10, transversely on the plate 1, one of said bars being located at the longitudinal center of the same, the other two being located substantially midway between the slots 6 and the ends of the plate. These bars may be made of the same material as the plate, and consists of relatively narrow strips having one end turned upwardly and 20 flush with the inner edge of the plate 1 to form finger holds 11 for the purpose of facilitating the lateral, sliding movement of the plate by the hand of the operator, such movement being limited, in an inward direction, by the outer ends of the slots 6. The outward sliding movement of the plate 1 is limited by the outer edge of the same coming into contact with keeper loops 12 secured to the upper face of the outer meeting rail 13 or lower rail of the upper sash 14, the inner edges of the keeper loops 12 being spaced from the abutting edges of the meeting rails a sufficient distance to permit a complete bridging of the gap by 30 the plate 1, when it contacts with the keepers.

35 These keepers are in exact alinement with the locking bars 9 which have their outer ends extended beyond the outer edge of the plate, to form tongues 15 having their side edges tapered to facilitate their entrance into the keepers 12, when the plate is slid or pushed outwardly, the width of the keepers being substantially the same 40 as the width of the bars 9 so that the tapered tongues may readily enter the same. The keepers comprise the inverted U-shaped housing formed of strips of metal and terminating in extended, oppositely disposed foot portions 16 which are held to the upper face of the outer rail 13 by screw 17.

45 The upper face of the tongues 15 are beveled, as at 18, so that when the same enter the keepers, a downward wedging action is caused to bear the strip tightly 50 against the upper faces of the meeting rails, and across the gap between the same, in a manner to effectually prevent the entrance

of air therethrough, the felt facing greatly aiding in such action, as will be understood.

60 From the foregoing, it will be seen that a simple, cheaply manufactured combination sash fastener and weather strip has been provided, which may be easily applied to any window in proper position for the plate to cover the gap, and to lock the sashes when desired, the parts being within easy reach and occupying so small a space as to not appear unsightly or cumbersome.

65 What is claimed is:—

70 1. A combined sash fastener and weather strip comprising a plate adapted to be mounted on the upper face of the meeting rail of a lower sash so as to slide transversely and rest upon the upper face of the meeting rail of the upper sash, means for preventing the upward movement of the plate, and for slidably retaining the same 75 on the first-mentioned meeting rail, tapered tongues projecting outwardly from the outer edge of the plate, and loop-shaped keepers attachable to the upper face of the outer meeting rail of the upper sash and 80 in alinement with said tongues and adapted to receive the same, when the plate is moved outwardly and across the gap between said meeting rails, to hold the sashes 85 from movement.

90 2. A combined sash fastener and weather strip, comprising an elongated plate adapted to be mounted on the upper face of the meeting rail of a lower sash, said plate having transverse slots therein, means insertible through said slots and engageable with the rail to prevent the upward movement of the plate relative to the rail and permit the same to be laterally moved to cross the gap between the meeting rails, felt padding carried by the under side of the plate to exclude the air, transverse strips secured to the plate and terminating in upturned finger-holds at the inner edge of the plate and 95 projecting beyond the opposite, outer edge of the plate to form tongues having their side edges tapered and their upper faces beveled, and loop-shaped keepers attachable to the upper face of the outer rail in line with the tongues and adapted to receive the tongues, when the plate is slid outwardly to lock the sashes together, and to prevent 100 ingress of air between the meeting rails.

105 In testimony, that I claim the foregoing as my own, I have hereto affixed my signature.

110 COLONEL COONEY.
